UNITED STATES PATENT OFFICE.

JAMES KILLEHER, OF CHIPIAWA, ONTARIO, CANADA, ASSIGNOR TO HARPER ELECTRIC FURNACE CORPORATION, A CORPORATION OF NEW YORK.

ELECTRIC TUNNEL KILN.

Application filed June 26, 1925. Serial No. 39,716.

This invention relates to electrically heated tunnel kilns. In firing many materials such as porcelain or other high-grade ceramic ware, the time during which the ware is maintained at certain definite temperatures is of the utmost importance and the major object of the present invention is to provide a tunnel kiln having means for electrically heating the same, which means is arranged and adapted to be controlled in such a manner that the ware passing through the kiln may be heated or cooled at any desired rate or may be maintained for any desired time at any one temperature.

15 Other objects and advantages will appear from the following description, taken in connection with the accompanying drawing wherein—

Fig. 1 represents diagrammatically in 20 horizontal section a tunnel kiln provided with electric heating elements arranged in accordance with one form of my invention.

Fig. 2 is a vertical section of such kiln taken on the line 2—2 of Fig. 1.

25 Fig. 3 is a circuit diagram showing the connections between the heater resistors and a controlling rheostat.

Fig. 4 is a top plan view showing an improved form of resistor which may be utilized in certain cases in carrying out my invention.

30 Fig. 5 is a section taken on the line 5—5 of Fig. 4, and

Fig. 6 is a section taken on the line 6—6 35 of Fig. 4.

Referring to Figs. 1 and 2, 1 represents the body or brickwork of the kiln and 2 the space through which the ware is moved as it is being fired. 3 and 4 represent resistors extending along the length of the tunnel and positioned in recesses in opposite sides thereof. Resistor 3 is formed of two resistance elements, 7 and 8, connected in series at 10, as indicated in Figs. 1 and 3, while resistor 4 40 is formed of two resistance elements, 5 and 6, which are connected in series as shown in Fig. 1. These resistance elements may consist of any material which is suitable for the dissipation of electrical energy and may consist of one piece or two, three or four pieces, arranged in multiple or in series. As shown in Fig. 1, the resistance elements 5 and 6 are adapted to be supplied with current from mains 15 and 16 and the resistance elements 55 7 and 8 are adapted to be supplied with cur-

rent from mains 17 and 18. Regarding for simplicity the elements 7 and 8 and assuming that the ware is entering the fire zone from the left in Fig. 1, this ware will first pass resistor 8 and then pass resistor 7. Assume that it is desired that the ware attain a certain temperature by the time it has reached the end of resistor 8, and be maintained at that temperature during its passage by the element 7. If both elements 7 and 8 had the same resistance and both carried the entire current from the mains 17 and 18, the amount of energy dissipated in the elements 7 and 8 would be equal. As the ware passes resistance element 8, sufficient energy must be dissipated in element 8 to raise the ware up to the desired temperature. If after passing terminal 10 the energy dissipated at 7 is equal to that at 8, the ware will be raised to an even higher temperature than that required because resistance element 8 has already supplied the ware with the amount of energy required to raise it to the specified temperature and therefore, merely to maintain the ware at the temperature which it has attained by passing resistance element 8, the energy dissipated in resistance element 7 must be only such as to take care of losses through the furnace walls, convection, and in chemical reactions in the ware, etc. In order to permit the use of two resistance elements in series, another small resistor, preferably made out of some resistance wire, is placed in the tunnel of the kiln as shown at 21. This secondary or shunt resistor has a plurality of taps such as 22, 23, 24, 25, 26. With one or another of these taps connected to the point 9 at the outer end of resistance element 7, and another tap connected to the point 10 between the elements 7 and 8, the current which passes through main 18, terminal 11, resistance element 8, divides at the terminal 10, one portion passing through resistance element 7 and the remainder through terminal 10, line 19, one of the taps such as 22 of resistor 21, a portion of resistor 21, another of the taps of resistor 21 such as tap 25, terminal 9, to the main 17. In this manner a portion of the current is shunted around resistance element 7, and resistance element 7 carrying less current than resistance element 8, the amount of energy dissipated in resistance element 7 is less than that dissipated in 8. If the shunt resistor or rheostat 21 were placed outside the furnace, the furnace

60 65 70 75 80 85 90 95 100 105 110

would be inefficient because the energy dissipated in rheostat 21 would be wasted. It is therefore placed inside the tunnel and may be utilized to heat up the ware before it 5 passes to the actual firing zone 7 and 8.

Resistance elements 5 and 6 are connected in much the same manner as resistance elements 7 and 8, the difference being that the resistance element 6 is shunted instead 10 of the resistance element 5. The connections as shown permit great flexibility in controlling the temperatures at various parts of the tunnel and permit a control whereby the ware is heated up gradually 15 and then passed through a short hot zone to finish the work of firing. It can be readily seen that the resistors or shunt rheostats 27 and 21 might be placed on the outgoing side of the kiln so as to extend the hot zone as 20 the ware cools off, for the purpose of annealing the ware. It will be apparent that various changes may be made in certain cases in the arrangement and connections between the various resistors.

25 In certain cases I may obtain a desired variation in temperature at various points in the tunnel by employing a resistor such as is shown in Figs. 4, 5 and 6. This resistor comprises two resistance elements 38 and 39 connected in series, end to end at 35, and is preferably formed of bars of carbonaceous material in which have been cut staggered slots, as indicated at 37. The portion of the resistor shown at the left in Fig. 4 is of 35 high resistance and that at the right is of low resistance, the difference in the resistances being due to the spacing apart of the staggered slots. Figs. 5 and 6, which are fragmentary vertical longitudinal sections 40 through the left and right hand portions of the resistor respectively, show the cross-sectional areas of the current paths in these two portions of the resistor.

45 The system of dissipating energy of varying amounts may utilize metallic resistors as well as graphite or carbonaceous resistors. These resistors may be round, cylindrical or other forms may be used.

I claim:

50 1. A tunnel kiln having an electric resistor heater located in one portion of the tunnel, and means to control the current through said resistor comprising a resistor heater rheostat located in another portion 55 of the tunnel and adapted to control the temperature of said latter portion of the tunnel.

60 2. A kiln having a tunnel through which ware is adapted to be passed, and means for heating the same comprising a resistance element extending along the tunnel, a second resistance element connected therewith and

extending along the tunnel at the rear of said first-named element, and a resistor heater rheostat adapted to shunt said first-named element, said rheostat being located in said tunnel to the rear of said second-named element and adapted to control the temperature of said latter portion of the tunnel.

65 3. A tunnel kiln having two electric heater resistance elements connected in series and extending along the tunnel one after the other, and a resistor heater rheostat in another portion of said tunnel adapted to control the current through said resistance elements, said rheostat being connected in shunt to one of said elements and adapted to control the temperature of said latter portion of the tunnel.

70 4. In a kiln having a tunnel through which material to be heat-treated is adapted to be passed, a pair of heater resistance elements located at one part of the length of said tunnel, a second pair of heater resistance elements located behind said first-

75 named pair, one element of one pair being electrically connected in series with one element of the other pair, and the other element of the one pair being electrically connected in series with the other element of the other pair, a third pair of resistance elements located at another part of the length of said tunnel, one element of said third pair being connected in shunt to an element of said first pair and the other element of said third pair being connected in shunt to an element of said second pair.

80 5. In a kiln having a tunnel through which material to be heat-treated is adapted to be passed, a pair of heater resistance elements located at one part of the length of said tunnel, a second pair of resistance elements located behind said first-named pair, one element of one pair being electrically connected in series with one element of the other pair, and the other element of the one pair being electrically connected in series with the other element of the other pair, a pair of rheostats located in another part of said tunnel, one of which is connected in shunt to one element of the first pair of resistance elements and the other of which rheostat is connected in shunt to the other element of said second pair of resistance elements.

85 6. A tunnel kiln having an electric resistor heater located in one portion of the tunnel and means to control the current through said resistor comprising a resistor heater rheostat located in a portion of the tunnel to the rear of said first-named portion and adapted to control the temperature of the rear portion of said tunnel.
